[57] CLAIM

The ornamental design for a vehicle mud flap, as shown and described.

DESCRIPTION

FIG. 1 is a perspective view of a vehicle mud flap showing my new design.

FIG. 2 is a side elevational view thereof.

FIG. 3 is a top plan view thereof.

FIG. 4 is a left end elevational view thereof.

FIG. 5 is a right elevational view thereof.

The side opposite to that shown in FIG. 2 of the drawing is understood to be flat and unornamented.

FIG. 1

FIG. 2

FIG. 3

FIG. 4

FIG. 5
